UNITED STATES PATENT OFFICE.

ALBERT E. WOODRUFF, OF OAK PARK, ILLINOIS, ASSIGNOR TO RESERVE HOLDING COMPANY, OF KANSAS CITY, MISSOURI, A CORPORATION OF DELAWARE.

TELEPHONE TRANSMITTER.

Application filed June 11, 1927. Serial No. 198,013.

This invention relates in general to telephone transmitters, but more in particular to transmitters in which the microphone element is of the carbon granular type.

5 It is an object of the invention to design a transmitter for use in the socalled cradle or hand type of telephone and the principal object is to design a transmitter of this type that will operate satisfactory regardless of 10 the position that it may be held in when in use.

Another object of the invention is the provision of means whereby relatively low values of current may be employed without 15 detracting in any way from the satisfactory operation of the transmitter.

In accordance with these and other objects, not specifically mentioned, but which will be readily apparent from the detailed 20 description, the electrodes of the microphone have been placed comparatively close together. They are of the same small diameter and area, so as to concentrate the current across the intervening space between 25 the electrodes, this space being filled with the comminuted material.

A feature of the invention resides in applying a flat insulating ring around the periphery of each electrode, and mounting 30 it with the electrode onto a metal stud. A relatively large surface is therefor presented to the granular carbons so they may be agitated, thereby eliminating packing, while the small electrodes present a small area to the 35 granules for the current to travel across.

This arrangement permits the use of low current values without the losses due to stray currents through low resistance paths in the carbon chamber, as has been the difficulty 40 encountered in previous transmitters.

The foregoing and other useful objects are attained through means which will be fully described hereafter, reference being had to the accompanying drawings, in which Fig. 45 1 is a rear view of the transmitter of this invention; Fig. 2 a cross section along the line A—A through the center of Fig. 1; while Fig. 3 shows in extended form the 50 relationship of the various parts and the general construction of the transmitter but-

ton or microphone element, with several of the parts in section.

Referring to Figs. 1 and 2 of the drawing the reference character 1 indicates the ring shaped metal back plate having a metal bridge piece 2 integral therewith, upon which the microphone elements are mounted. A ring shaped face plate 3 screws into a threaded flange around the periphery of the back plate 1 and holds the diaphragm 4 in place. The foregoing comprises essentially the means for mounting the transmitter, and while the usual rear metal casing or covering for the transmitter and heavy metal face plate and mouth piece have not been shown, 55 it is very readily conceived how these parts may be attached. While this embodiment of the invention was conceived primarily for a hand or cradle telephone it may readily be adapted for other uses than that shown, by 60 anyone skilled in the art.

The metal diaphragm 4 is slightly turned out at its periphery and its edge rests against a pair of rings 31, made of insulating material and placed in the face plate 3 so as to 65 cushion the diaphragm 4 on the transmitter casing. The face plate 3 forces the rings 31 against the diaphragm 4 and holds the diaphragm under constant tension. The diaphragm 4 is mounted between two locking nuts 8 on the stud 12. A leg of the damper spring 6 is insulated from and extends on 70 each side of the diaphragm 4 so as to dampen any excessive speech vibrations. This damper spring is held in place on the plate 5 by 75 a pair of screws, on the plate 1.

The microphone elements consist essentially of a metal cup 16 provided with exterior screw threads adapted to receive a metal clamping ring 15. Between this ring 80 and the edge of the cup 16 there is clamped the metal auxiliary diaphragm 11, together with the annular paper ring 26, which takes up any irregularities in the surfaces between the metal diaphragm 11 and the clamping ring 15. The metal stud 12, has the polished face carbon electrode 13 suitably fastened to the enlarged face of the stud, and has an annular ring 14 of insulating material surrounding the edge of the electrode 13, also 85 100

fastened to the face of the stud. The nut 9 with the cup shaped metal member 10 on the extended portion of the stud 12, clamps the stud onto the center of the auxiliary diaphragm 11, so that any vibration of the main diaphragm 4 is transmitted to the auxiliary diaphragm 11 through the stud 12. Located directly opposite the electrode 13 is a second electrode 20 of the same diameter, which is 5 suitably mounted on the enlarged face of the metal stud 18. Surrounding the edge of the electrode 20 and also fastened to the stud 18 is an annular insulating ring 19 slightly larger than the surface of the stud 18 and similar to the ring 14 of the other electrode 13. Another insulating ring 30 is held against the rear surface of the stud 18. Attached to the inside cone shaped surface of the metal cup 16 is a lining 17 consisting 10 of insulating material. The stud 18 rests against the small end of the cup 16, the insulating lining 17 and the ring 30 insulating it therefrom. It will thus be seen that the stud 18 is completely insulated from the 15 chamber formed by the cup 16, and in no way can the fine carbon granules contained therein reach it. The stud 18 is clamped to the bridge plate 2 by a nut 24 and this stud which has an insulating bushing 21 surround- 20 ing it, also supports the cup 16, the metal terminal plate 25, the insulator 27 and on the top of the bridge 2, the insulator 22 and terminal plate 23. The terminal plates each have a screw 28 and 29 to which the wires of 25 the transmitter are attached.

By referring to Fig. 3 it will be apparent how the microphone element is assembled. The stud 12 containing the metal diaphragm 11 on the rear of the enlarged face of the 30 stud, and the insulating annular ring 14, surrounding the small electrode 13, on the front, is placed in the clamping ring 15, with the annular spacing ring 26 between the metal diaphragm 11 and the clamping ring. The 35 metal cup 10 is clamped to the diaphragm on the stud 12 by the nut 9 so that the periphery of the cup will coincide with the periphery of the enlarged face of the stud on the opposite side of the diaphragm. This 40 is so that that diaphragm will not buckle or bend. The stud 18 with the annular insulating ring 30 on the rear of its enlarged face, and the annular insulating ring 19 surrounding the electrode 20 on its front, is 45 passed through the hole of the cup 16. This hole is made large enough so that the stud will not touch the sides. It will therefore be seen that this stud 18 is completely insulated from the cup 16. After the stud 18 and the 50 cup 16 are mounted on the bridge piece 2, the clamping ring 15 is screwed onto the cup and the unit is then complete.

The electrical circuit of this transmitter is as follows: from the terminal 28, through 55 the terminal plate 25, through the cup 16

to the metal diaphragm 11, through the stud 12 to the electrode 13, and thence through the comminuted material to the electrode 20 and the stud 18. From the stud 18 the current passes to the terminal plate 23 to the 60 terminal 29. From the above traced circuit it will be noted that the cup 16 is completely insulated from the stud 18.

The foregoing describes one embodiment of the invention and it will be seen by referring to the drawings that the electrodes 13 and 20 which are placed relatively close together are of a smaller size than have been used heretofore. Due to the small space between the electrodes, occupied by the comminuted material, which is also the point where the greatest agitation of the granules takes place, relatively low values of current can be used in this transmitter, while the sloping cone shaped walls of the cup 16 assists in restricting the carbon granules at the point where the greatest percentage of agitation takes place. This considerably reduces the tendency of the carbon to pack. The insulating annular rings 14 and 19 75 around the electrodes, concentrates the current directly onto the electrodes, and ring 14 on the stud 12, which is connected directly to the main diaphragm 4 and therefore responds to any sound vibrations impinged 80 thereon, agitates practically the whole mass of the comminuted material and no low resistance leakage path for the current is formed. This would be practically equivalent to having large electrodes to agitate the 85 granules, but in this case the electrodes are 90 comparatively small so that the maximum amount of resistance is obtained across the electrodes.

The exposed surfaces around the periphery of the flat face of the stud 12, and also part of the auxiliary diaphragm 11, which are in direct contact with the carbon granules, form a means whereby a reserve supply 95 of granules is kept, but due to the comparatively long distance for the current to travel to the electrode 20 and the resistance of the granules between, there will be very little 100 if no current flow over this path.

The conical shape of the electrode chamber and the exposed surfaces described in the above paragraph and around the periphery of the electrodes eliminates any possibility of the transmitter being open circuited, irrespective of the position of it 110 when in use.

Having described this invention, what is considered new and what is desired to have protected by Letters Patent is pointed out 115 in the appended claims.

1. In a telephone transmitter, an electrode chamber, a metal stud projecting into each end of said chamber, electrodes projecting into said chamber from each of said studs, comminuted material in said chamber, annu- 120

lar rings on said studs around said electrodes for insulating said studs from said comminuted material, means for moving one of said studs to agitate said comminuted material, a maximum amount of movement taking place between said electrodes, while the surfaces of said studs covered by said annular rings agitates said material an amount to prevent packing thereof and always keep the space between said electrodes filled with said material.

2. In a telephone transmitter, an electrode chamber containing comminuted material, a pair of opposite spaced metal studs projecting into each end of said chamber, an electrode on each of said studs also projecting into said chamber, said electrodes spaced apart in said chamber a smaller amount than said studs, annular insulating rings around said electrodes on said studs projecting into said chamber a lesser amount than said electrodes but a greater amount than said studs, means for moving one of said studs to agitate said comminuted material, a greater amount of agitation taking place between said electrodes and a lesser amount between the insulated rings on said studs so as to assist in maintaining all of said comminuted material in constant motion.

3. In a telephone transmitter, an electrode chamber containing comminuted material, a pair of metal studs mounted opposite each other in each end of said chamber, said studs each having a flat annular surface extending into said chamber, annular insulating rings on the surface of each stud extending into

said chamber, an electrode inside said annular ring and on each stud and projecting into said chamber beyond the edge of said ring, means for agitating the whole surface of one of said studs in said chamber to agitate said comminuted material, the insulated ring on the surface of each stud agitating said material an amount to prevent packing thereof, while the maximum amount of agitation occurs between the surfaces of said electrodes.

4. In a telephone transmitter, an electrode chamber containing comminuted material, a metal stud closing one end of said chamber and having a large surface extending into the chamber, a small rear electrode projecting from said stud into said electrode to insulate said stud from said comminuted material, a movable diaphragm closing the opposite end of said chamber, a second stud mounted on said diaphragm in said chamber and having a large surface therein, a small front electrode projecting from said second stud into said chamber, an annular insulating ring surrounding said front electrode on said second stud, means for moving said diaphragm to agitate said comminuted material, the maximum amount of movement taking place between said electrodes, while the large insulated surfaces on the studs around said electrodes assists in said movement to agitate said material to prevent packing thereof and restrict the flow of current only between said electrodes.

In witness whereof, I hereunto subscribe my name this 9th day of June, A. D. 1927.

ALBERT E. WOODRUFF.
